Dec. 1164

Allen Leonard, of Hartford, Conn.
Letters Patent No. 1164. Dated Nov. 1. 1859.

The schedule referred to in these Letters Patent and making part of the same.

To all whom it may concern:

Be it known that I, Allen Leonard, of the City & County of Hartford, and State of Connecticut, have invented or produced a new and original design for a Base of Casters &c, and I do hereby declare that the following is a full and exact description of the same.

In the accompanying Photographs, is presented to the eye, the architectural shape, and form or Base, with its elevated column based thereon.

A. is the base proper.

B. the elevated column.

C. the lower projection therefrom.

D. the edge of base proper.

E. the mouldings in Bass-relief.

F. the fulcrum.

Upon the lower projection, and upon the summit, or the edge of the highest part of the base proper, is a configuration partaking of the form, or outline, of the Grecian architectural mouldings, in Bass-Relief with a beaded edge in place of a fillet, presenting a bold and highly ornamental Design, for a base and fulcrum for a Server or Caster, ring or rim (for holding various articles, which base I propose to mount upon pedestals or feet, of different patterns).

What I claim and desire to secure by Letters Patent, is The shape and configuration as described for a center base.
